JAMES A. GRAY, OF SAN FRANCISCO, CALIFORNIA, ASSIGNOR TO AMERICAN CAN COMPANY, OF NEW YORK, N. Y., A CORPORATION OF NEW JERSEY.

APPARATUS FOR CUTTING AND APPLYING RING-LINERS TO CAN-COVERS.

1,121,009.

Specification of Letters Patent.

Patented Dec. 15, 1914

Application filed October 31, 1912. Serial No. 728,937.

To all whom it may concern:

Be it known that I, JAMES A. GRAY, a citizen of the United States, residing in the city and county of San Francisco and State of California, have invented certain new and useful Improvements in Apparatus for Cutting and Applying Ring-Liners to Can-Covers, of which the following is a specification.

10 The present invention relates to an improved machine for cutting ring liners from a traveling web of paper, depositing the same within a seat of a rotary carrier, supplying a can cover within said seat of the 15 carrier in advance of the ring liner, and forcing the placed ring liner within or onto the flange of the can cover, the various steps in the operation of the machine being automatically and successively carried out 20 through the action of a series of inter-connected instrumentalities so arranged relative to each other and timed as to their action of movement as to come into play at predetermined moments; the object of the 25 invention being the production of an automatically operated machine for the cutting and placing of the ring liners relative to the can cover which shall be simple of construction, positive in its action, durable and composed of comparatively few working parts.

To comprehend the invention, reference should be had to the accompanying sheets of drawings, wherein—

Figure 1 is a plan view of the improved machine disclosing the relative position of the cutting punch for severing the ring liners from the traveling web, the mechanism for imparting reciprocating motion thereto, the barrel or magazine for receiving the central disk severed from the traveling web in the cutting of the ring liners, the mechanism for delivering the can covers to the rotary carrier (not shown) the disposition of the web of paper from which the ring liners are cut, the means for feeding the web across the front of the cutting punch, and the feed mechanism for the can covers. Fig. 2 is a longitudinal sectional view taken on line $x-x$ Fig. 1 of the drawings, viewed in the direction of the arrow a , illustrating more particularly the drive mechanism for imparting reciprocating movement to the cutting punch and transmitting an intermittent or step rotation to the carrier for the can covers and ring liners.

and the means for actuating the reciprocating plungers for forcing the ring liner onto the circumferential flange of the can covers. Fig. 3 is a vertical sectional view taken on line $y-y$ Fig. 2 of the drawings, the barrel or magazine for the central disk cut from the traveling web being removed and the web of paper being partly broken away, said view disclosing the rotatable carrier for the can covers and ring liners, the means for delivering the cut ring liners to the seats of the said carrier, the feed mechanism for the can covers, the position of the traveling web, the feed means for advancing the web through the machine in advance of the cutting punch, and the discharge runway for the lined can covers. Fig. 4 is a detail view of one of the cut ring liners. Fig. 5 is a cross sectional view of one of the can covers, within the circumferential seat of which formed by the inturned edge of the flange of the can cover is forced the ring liner.

In the drawings, the numeral 1 is used to designate any suitable form of a supporting frame capable of sustaining the various working parts of the apparatus, and 2 a bed mounted thereon and within guide ways 3 of which works the reciprocating slide 4 carrying at its inner end a detachable punch 5, and a die ring 5', Figs. 1 and 2 of the drawings. The said slide 4 is actuated by a cam 6 acting against rollers 7 and 7' mounted within a cross head 8 secured to and carried by the outer end of the slide 4, the said actuating cam 6 being mounted on a cross-shaft 8' working in bearing boxes 9.

Between the punch 5 and the die ring 5' screwed to the slide 4 there is interposed an ejector ring 5^a, which is permitted slight movement under pressure of the punch 5. From the said ejector ring projects a series of bolts c which extend through bores in a circular shoulder d of the reciprocating slide 4 and act against a collar e slidably mounted on said slide and which is engaged by a finger f fixed to and upwardly projecting from the frame of the machine on the return stroke of the slide 4 to force the ejector ring a slight distance beyond the die ring 5' to force the cut ring liner from off the punch.

The shaft 8' is driven in any suitable manner, preferably by means of a power belt working over a belt pulley 9' secured to

to one end thereof, the said shaft at its opposite end carrying a gear wheel 10 which meshes with a gear 10' for transmitting rotation to a cross shaft 11 situated below the shaft 8' for imparting motion to the hereinafter described actuating means for giving a step rotation to the carrier containing the can covers and liner rings to be applied thereto.

- 10 In front of the punch 5 and held a slight distance therefrom is situated a die ring 12, the same being loosely held to the inner end of a cylindrical magazine 12' and normally held outwardly pressed by the springs *a*, 15 the magazine being attached to the frame of the machine, and in line with the punch 5 to receive the waste material or central disk cut from the web out of which the liner rings are formed, the die ring 12 being held 20 to the magazine 12' by the securing collar *b* united in any suitable manner to the said magazine.

The paper web 13 out of which the ring liners are cut is fed transversely through the 25 machine between the punch 5 and the magazine 12' by means of the vertically disposed guide feed rollers 13' and 14, the said web unwinding from a spool 14' loosely mounted on a short vertical stud 15 situated at one 30 side of the bed 2 of the frame 1—Figs. 1 and 3 of the drawings. The guide roller 13' is a positively driven one, while the roller 14 is loosely mounted on a stud 14^a upwardly projecting from a slide rod 14^b and 35 is frictionally driven, and the said roller 13' is driven by means of a bevel pinion 15' secured to the lower end thereof meshing with a bevel pinion 16 on a longitudinally disposed shaft 16' working in bearing 17 at 40 one side of the machine. This shaft 16' at its outer end carries a bevel pinion 17' which is engaged and driven by a bevel pinion 18 on the rotating cross shaft 11, having rotation imparted thereto from the 45 drive shaft 8' through the described gear connections.

The web 13 is advanced through the machine only when frictionally engaged by the 50 guide and feed rollers 13' and 14, but the travel of the web is an intermittent one due to the fact that the roller 14 is only in engagement therewith at pre-determined moments, being normally held out of engagement or away from the surface of the web 55 by the tension of the spring 13^a connected to and acting against the slide rod 14^b. At its outer end the said slide rod carries a roll 13^b loosely mounted on a laterally projecting stud 13^c and said roll is intermittently engaged 60 by a cam 15^a on the drive shaft 8' acting thereagainst. When the cam 15^a acts against the roll 13^b the slide rod 14^b is forced forwardly, carrying therewith the guide feed roller 14 for frictional engagement 65 with the web 13, which is then firmly

held between the rollers 13' and 14 and fed forward by the rotary action of the roller 13'.

To the opposite end of the cross-shaft 11 to that carrying the bevel pinion 18 is secured beyond the gear 10' a bevel pinion 18', which meshes with a bevel pinion 19 secured to the outer end of a short longitudinally disposed shaft 19', carrying at its inner end a bevel pinion 20 meshing with a 75 similar pinion 20' on the lower end of a short vertical shaft 21. This shaft at its upper end is provided with a gear 22, which meshes with and imparts rotation to a gear ring 22' encircling the lower end portion 80 of a can head holder 23, and said ring in turn meshing with a gear 23' imparts rotation to a short vertically disposed shaft 24 carrying a screw disk 24', a companion screw disk 25 being secured to the short vertical shaft 21 to which is attached the gear 22 and the bevel pinion 20'. The said screw disks 24' and 25 are located below the bottom of the can head holder 23 and serve as a screw feed means for delivering the horizontally disposed can covers or heads 26 from within the holder 23 into a downwardly inclined chute or runway 26', the 85 said heads or covers as they leave the screw feed bearing against a bridge piece or plate 90 27 located within the upper portion of the chute or runway 26' and are thrown from a horizontal into a vertical position—Fig. 3 of the drawings.

Within the frame of the machine and on 100 a longitudinal shaft 28 working in bearings 28' thereof is situated a vertically disposed rotatable carrier disk 29, whose movement in the direction of its rotation is designated by arrow *a* on Fig. 3 of the drawing, 105 and the said carrier disk is provided with a plurality of transversely circumferentially disposed openings or seats 30, within each of which work a pair of opposing normally spaced hollow reciprocating plungers 31 110 and 32, the stems of which extend through guide openings 32' and each of said stems carrying at its outer end a depending roll 33. These rolls work within a circumferential cam groove 33' in the fixed spaced disks 115 34 between which the carrier disk 29 revolves, and during the rotation of the said carrier disk the plungers are moved toward and from each other for applying the hereinafter described ring liner onto the flange 120 of the can head or cover—Fig. 2 of the drawings.

Each of the circumferential openings or 125 seats 30 is intersected by a segmental peripheral opening 34', and a similar opening 34^a through which the ring liners 35 and the can covers 26 respectively are deposited vertically within the seats 30 between the opposing faces of the plungers 31 and 32, the can heads or covers 26 being delivered 130

into the seat 30 through the opening 34² from the inclined chute or runway 26' on an opening 34² being placed into registry with the lower or discharge end thereof; 5 while the ring liners 35 are deposited through the opening 34' into the seat 30 as dropped from the cutting punch 5 of the slide 4. When within the seat 30 the can cover and ring liner stand in vertical position between the plungers 31 and 32 and in front of the spring held chuck 31^a of the plunger 31, with the ring liner in advance of and in alinement with the flange 26^a of the cover 26, so that on the plungers being 10 brought together the said ring liner 35 will be forced onto the circumferential flange of the can head or cover 26, during which seating of the ring liner the chuck 31^a is gradually moved within the plunger 31. 15 By reason of the disposition of the cam grooves 33' of the fixed disks 34 the plungers are held in such inwardly pressed position until by the rotary movement of the carrier disk the rolls 33 are carried 20 within the outwardly extended portion of the cam grooves, by which time the opening 34' of the seats 30 will be in line with the discharge runway 36 and the plungers or pistons 31 and 32 moved away from each 25 other or separated, when tension of the springs 36' coming into play forces outwardly the chuck 31^a to unseat the can head or cover 26 with its applied liner ring and place the same immediately over the 30 opening 34' through which the same escapes by gravity into the discharge runway or chute 36 for delivery to a suitable place of deposit.

An intermittent or step rotation is imparted to the shaft 28 and the carrier disk 29 secured thereon by means of the mated worm gear 37 secured to the outer end of the shaft 28, which worm gear is intermittently engaged and given a part rotation by the worm section 37' of a disk 38, secured to the drive shaft 11 meshing therewith at given intervals. The rotary motion of the drive shaft is thus transmitted to the shaft 28 and the carrier disk 29 for imparting a step or intermittent rotation thereto.

During the forward stroke of the slide 4 the punch 5 and die ring acting against the web 13 forces the same firmly onto the magazine 12', the punch 5 acting first to eat the central disk from the web and the die ring 5' associated with the punch 5 by the continued movement of the slide 4 co-acting with the die ring 12 cutting the ring liner 35 from the web 13, the removed central disk or body of the ring moving into the magazine 12'. The liner ring adheres to the die ring 5' until on the outward stroke of the slide 4 and punch 5, the collar e engages with the bracket f, forcing the ejector

ring 5^a beyond the face of the die ring 5' and punch 5 to release the cut liner ring 35, which escapes into and through the guide-way 38' and is deposited into one of the seats 30 of the carrier disk through the opening 34' communicating therewith. On the outward or return stroke of the punching mechanism, the feed devices for the web 13 advance the same to place or position an uncut portion thereof in advance of the punch mechanism, the said web remaining at rest during the cutting stroke of the punching mechanism, which intermittent or step feed movement of the web 13 is controlled by the before described interconnected devices.

The working stroke of the punching mechanism, the movement of the intermittent traveling web, the rotation of the carrier disk, and the feed mechanism for the can heads or covers are so controlled, regulated and timed with respect to each other that the various described actions successively come into play at predetermined moments, so that each part performs its desired work at the proper moment with respect to the other working parts of the apparatus, thereby constituting an automatic machine for cutting liner rings, assembling can heads or covers and the liner rings, forcing the liner rings onto the flange of the can heads or covers, and discharging the can heads or covers with the ring liners applied thereto.

I am aware that various changes may be made in the working parts and the details of construction herein shown and described without causing a departure from the spirit of the invention, and I do not wish to be understood as so restricting, limiting or confining the invention, but on the contrary desire to cover the invention broadly irrespective of the details of construction of the working parts of the apparatus for carrying the same out; although the arrangement and construction of the working parts shown and described is preferred.

Having thus fully described my invention what is claimed as new and is desired to be protected by Letters Patent is—

1. In an organized apparatus for cutting fibrous ring liners and assembling said liners and can covers and applying the cut ring liner to the flange of a can cover, the combination with a reciprocating cutting die punch, of means for positioning a fibrous web in advance thereof, a rotary carrier co-acting therewith and provided with circumferentially disposed seats for the reception and holding therein of can covers and ring liners to be applied thereto in spaced relation to each other, opposing reciprocating plungers working in said seats, devices for moving said plungers toward each other to force the ring liner onto the flange of the

- 1 can cover and separating the same during the rotary movement of the carrier to release the can cover with its applied liner ring, and inter-connected mechanism for actuating the die plunger, transmitting feed movement to the web, and imparting motion to said rotary carrier.
2. In an organized apparatus for the described purpose, the combination with a reciprocating die punch, of an ejector device carried thereby, means for advancing a fibrous web in front of the die punch for the removal therefrom of a ring liner of less diameter than the diameter of a can cover, rotary mechanism for receiving a can cover and the ring liner holding the same in spaced relation relative to each other, reciprocating devices working therein for forcing the ring liner onto the flange of the can cover, and inter-connected instrumentalities for imparting reciprocating movement to the die plunger, step feed movement to the web, and actuating the mechanism for receiving the can covers and ring liners and applying the said liner to the flange of the can covers.
3. In a machine for the described purpose, the combination with mechanism for receiving a web and cutting therefrom a ring liner of less diameter than the diameter of a can cover, of means for receiving a can cover and the cut ring liner and holding the same in spaced relation one to the other, opposing reciprocating devices working within and carried by said means for applying the said ring to the flange of the can cover, and inter-connected instrumentalities for imparting movement to the mentioned cutting mechanism and applying means for the ring liners.
4. In a machine for the cutting of fibrous ring liners from a traveling web and applying the same to the flange of a can cover, the combination of means for imparting a step feed movement to a fibrous web, of mechanism for cutting a ring liner therefrom of less diameter than the diameter of a can cover, rotary means coacting with said mechanism for receiving a can cover and the cut ring liner and holding the same in spaced relation relative to each other, and oppositely reciprocating devices carried by the said rotary means and thrown into action by the movement thereof for forcing the cut ring liner onto the flange of the can cover.
5. In a machine for the described purpose, the combination with reciprocating mechanism for cutting a ring liner of less diameter than the diameter of a can cover from a web, of devices for feeding and positioning a web relative to said mechanism, and means for receiving a can cover and the cut ring liner and holding the same in spaced relation relative to each other, and oppositely reciprocating devices working within said means and carried thereby for applying the said liner to the flange of the can cover.
6. In a machine for the described purpose, the combination with a die punch, of an ejector device carried thereby, means for feeding and positioning a fibrous web in front of the die punch for the cutting of a ring liner therefrom of less diameter than the diameter of a can cover, mechanism for receiving and holding a can cover and the severed ring liner in spaced relation relative to each other, oppositely reciprocating devices associated therewith and carried thereby and thrown into action by said mechanism for applying the ring liner to the flange of the can cover, and inter-connected instrumentalities for imparting motion to the mentioned parts of the apparatus.
7. A machine for the described purpose, the same comprising reciprocating mechanism for cutting a ring liner of less diameter than the diameter of a can cover from a fibrous web, means co-acting therewith for receiving a can cover and the said ring liner and holding the same in spaced relation relative to each other, and devices carried thereby and thrown into action by the movement of the said means for forcing the ring liner onto the flange of the can cover.
8. In an organized apparatus for the described purpose, the combination with a reciprocating die punch, of an ejector device carried thereby, a magazine in alinement with the die punch, means for feeding a fibrous web between the said magazine and punch, mechanism for imparting reciprocating motion to the said punch for the cutting of a ring liner of less diameter than the diameter of a can cover and from the web and the discharging of the same, rotary mechanism for receiving a can cover and the ring liner and holding the same in spaced relation relative to each other, and oppositely reciprocating devices associated with and carried by said mechanism and thrown into action by the movement thereof for applying the ring liner to the flange of the can cover and releasing the cover with its applied ring liner.
9. In an organized apparatus for the described purpose, the combination with a reciprocating punch for the cutting of a paper ring liner of less diameter than the diameter of a can cover, of means for feeding a fibrous web and positioning the same relative to said punch, rotary means for receiving the cut ring liner and a can cover and holding the same in spaced relation relative to each other, and devices carried by said means for forcing the cut liner onto the flange of the can cover.
10. In an apparatus for the described purpose, the combination with a rotatable carrier provided with circumferentially dis-

posed seats, of devices for delivering a can cover into said seats, mechanism for cutting a ring liner of less diameter than the diameter of a can cover from a fibrous web 5 and discharging the same into the seats in advance of the can cover, and devices associated with said carrier and thrown into action by the movement thereof for forcing the ring liner onto the flange of the can 10 cover and releasing the cover with the ring liner applied thereto.

11. In a machine for the described purpose, the combination with a reciprocating die punch for cutting from a fibrous web a 15 ring liner of less diameter than the diameter of a can cover, of an ejector carried thereby, a coacting die ring opposing the die punch, devices for intermittently feeding a web of paper between the die punch 20 and die ring, means for imparting reciprocating movement to the die punch for the cutting of a ring liner from the said web, mechanism for receiving a can cover and the cut ring liner and reciprocating devices carried by said mechanism for forcing the ring liner onto the flange of the can cover.

12. In a machine for the described purpose, the combination with mechanism for cutting a ring liner of less diameter than the 30 diameter of a can cover from a web of paper, of a rotary carrier provided with circumferentially disposed seats for receiving a can cover and the cut ring liner and holding the same in spaced relation relative to 35 each other, and oppositely reciprocating devices working within the said seats of the carrier for forcing the ring liner onto the flange of the can cover.

13. In a machine for the described purpose, the combination with die punch mechanism for cutting ring liners of less diameter than the diameter of a can cover from a fibrous web of paper, of devices for positioning a web relative to the cutting 40 dies, rotary means associated with said punch mechanism for receiving a can cover and the cut ring liner and holding the same in spaced relation relative to each other, and

devices working within said means and thrown into action by the movement thereof 50 for applying the said ring liner to the flange of the can cover.

14. In a machine for the described purpose, the combination with a reciprocating die punch for the cutting of a fibrous ring 55 liner of less diameter than the diameter of a can cover; of an ejector associated therewith, means for positioning a fibrous web in advance of the die punch for the cutting of a ring liner therefrom, devices for imparting a step feed motion to the web, a rotatable carrier provided with a series of circumferentially disposed seats for receiving can covers and the cut ring liners and holding the same in spaced relation relative 60 to each other, means for supplying can covers to the seats of the carrier, a pair of opposing plungers working within said seats for forcing the ring liners onto the flange of the can covers, and devices for imparting 65 reciprocating motion to said plungers.

15. An organized apparatus for the cutting of a paper ring liner from a traveling web and applying the same to the flange of a can cover, the same comprising a reciprocating die for the cutting of an annulus of less diameter than a can cover from a web of paper, means for positioning a web in advance of the die punch, an associated 75 rotary carrier having openings therein for the reception of the cut liner and the can cover and for the holding of the same in spaced relation to each other, and oppositely moving reciprocating means acting on the said positioned ring liner and cover for the 80 forcing of the liner into the flange of the cover, said reciprocating means being thrown into action on the movement of the 85 rotary carrier.

In testimony whereof I have signed my 90 name to this specification in the presence of two subscribing witnesses.
